UNITED STATES PATENT OFFICE.

HUGO E. RIEGEL AND DAVID F. HORNING, OF ST. PAUL, MINNESOTA, ASSIGNORS TO
THE SUPER GAS PRODUCER SALES CO., A CORPORATION OF SOUTH DAKOTA.

HYDROCARBON-GENERATOR.

1,214,370.

Specification of Letters Patent. Patented Jan. 30, 1917.

Application filed April 8, 1916. Serial No. 89,948.

To all whom it may concern:

Be it known that we, HUGO E. RIEGEL, and DAVID F. HORNING, citizens of the United States, residing at St. Paul, in the 5 county of Ramsey and State of Minnesota, have invented certain new and useful Improvements in Hydrocarbon-Generators, of which the following is a specification.

Our invention relates to improvements in 10 oil burners adapted to be positioned in the fire box of the ordinary construction of stoves and ranges and to be utilized to deliver heat to the stove lids and oven, its object being to provide a construction 15 adaptable to the use of either kerosene or gasoline.

By means of our novel features of construction and combination we claim to secure a more efficient burner of this class 20 than ordinarily employed.

To this end the invention consists in the features of construction, combination, and arrangement of parts hereinafter described and claimed.

25 In the accompanying drawings forming part of this specification, Figure 1 shows a side elevation of our improved burner; Fig. 2 is a diagrammatic side view; Fig. 3 is an elevation of a range, broken away, and with 30 a burner arranged therein; and Fig. 4 is a section on line 4—4 of Fig. 1.

Referring to the drawings, A represents the fire box of an ordinary stove or range and B the grate bars thereof.

35 In carrying out our ideas we employ a horizontally disposed gas supply pipe 2 having a gas inlet portion or tube 3 centrally connected with the underside thereof and extending outwardly parallel thereto, 40 the gas inlet tube having an open outer end. The gas inlet tube is formed with lateral branch air inlet tubes 4 formed with feet 5 to rest upon the grate. The supply tube 2 is supported between the ends 6 of 45 the burner by means of rod 7 extending through the gas supply tube and through the burner ends, the parts being held together by a nut 8 threaded upon the end of the rod. The burner ends are formed with feet 9 corresponding with the feet 5. The 50 burner ends are in the form of branching conduits 10. Between the upper ends of the opposite conduits are supported the burner tubes 11 through the medium of rods

12 extending through the burner tubes and 55 burner ends and carrying fastening nuts 13. The burner tubes are formed upon their upper sides with a plurality of spaced slots 14 constituting gas outlet openings. By loosening the nuts upon the ends of the 60 rods the burner tubes may be turned to adjusted positions to regulate the discharging direction of the gas through the jet openings. Supported upon the top of the supply tube 2 and preferably formed integral 65 therewith is a generating pan 15.

For the purpose of supplying the oil to the burner and generating the same we provide the following parts. An oil inlet tube or pipe 16 leads from a source of supply 70 outside the range, being provided with a controlling valve 17. The pipe 16 is directed over the top of the generator pan to constitute a generator pipe 18, as shown in Fig. 1, being thence bent back upon itself 75 between the burner pipes 11 and thence downwardly adjacent the end of the front end of the burner with the outlet end 19 of the generator pipe 18 projected into the inlet end of the tube portion 3, the outlet 80 end 19 being fitted with a suitable valve 20.

As heretofore described the burner tubes may be turned into adjusted positions by the loosening of the nuts upon the securing rods to change the angle at which the flame 85 from the burner openings 14 strike the intermediate generator tube 18. This allows the use of different oils as kerosene or gasoline, a more direct striking of the flame against the generator tube being required in the use 90 of kerosene than in the use of gasoline.

In use, the burner will be positioned within the fire box, as shown in the drawings, and connected with a suitable exterior source of oil supply. In starting the burner, the valve 17 will be open to allow the oil to pass into the generator tube, the generator pan being filled with suitable generating material, as alcohol, and ignited to heat and turn the oil in the generating tube into gas. The 95 valve 20 then being opened will direct the generated gas through the inlet tube portion 3 and supply tube 2 and end conduits 10 of the burner to the burner tubes. From the burner tubes the gas will be discharged 100 from the discharge openings 14 to heat the lids of the stove and the oven wall, and at the same time to further heat the portion of

the generator pipe located between the burner tubes to keep up the generation of the gas.

By means of the adjustable support of the 5 burner tubes the discharging direction of the flames from the burner tubes may be varied at will not only to assist in adapting the device to utilize kerosene or gasoline, as desired, but to adjust either or both of the 10 burner tubes to direct the flames against surrounding parts of the fire box as the stove lid or oven wall.

We thus secure a construction with a large 15 range of adjustability and through the distribution arrangement of the gas supply conduits and air inlet conduits secure the maximum amount of efficiency.

We claim:

1. A burner of the class described comprising a horizontally disposed gas supply tube, conduits extending upwardly and radially from the ends of said supply tube, burner tubes connecting the upper ends of 20 said conduits, and a fuel supply tube passing 25 between the burner tubes and discharging into the gas supply tube.

2. A burner of the class described comprising a horizontally disposed gas supply tube, a pair of horizontally disposed burner 30 tubes rotatably mounted above said supply tube and communicating therewith, and a

fuel supply tube passing between said burner tubes and thence into position for discharging into said gas supply tube.

3. A burner of the class described comprising a horizontally disposed gas supply tube, a pair of horizontally disposed burner tubes rotatably mounted above said supply tube and communicating therewith, a generator pan supported by said gas supply tube, 40 and a fuel supply tube passing between said burner tubes and thence over said pan and into position for discharging into said gas supply tube.

4. A burner of the class described comprising a gas supply tube and a gas inlet portion, said gas inlet portion being formed with lateral air inlet openings, a pair of burner tubes rotatably mounted above and communicating with said gas supply tube, 45 and a fuel supply tube passing between said burner tubes and into position for discharging into the inlet portion of said gas supply tube.

In testimony whereof we affix our signatures in presence of two witnesses.

HUGO E. RIEGEL.
DAVID F. HORNING.
